UNITED STATES PATENT OFFICE

2,007,830

ARMATURE WINDING MACHINE

James L. McNeill, Richmond, Ind.

Application July 11, 1934, Serial No. 734,634

5 Claims. (Cl. 242—13)

One of the objects of my invention is the provision of a machine for accurately winding wire on armatures of different sizes, and which will produce neatly wound armatures.

5. Another object of my invention is the provision of a device in which an armature can be quickly clamped in the correct position, and which will securely hold the armature while being wound with wire.
10. Another object of my invention is the provision of an armature winding machine which may be either manually or power operated.

Still another object of my invention is the provision of a winding device which can be economically manufactured, is constructed of a minimum number of parts, and which is not likely to get out of order under extremely hard usage and in continuous operation.

Other objects and advantages of my invention will suggest themselves in the course of the following description, and that which is new will be correlated in the appended claims.

I am aware that armature winding devices are being used at the present time, but in my armature winding machine, I have provided a machine which may be used for winding various sizes of armatures without any changes in the machine whatsoever.

The most satisfactory manner of carrying out the principles of my invention in a practical, economical, comprehensive and efficient manner is shown in the accompanying one sheet of drawing, in which—

Figure 1 is a top plan view of my machine.

35. Figure 2 is a front elevation of my machine, taken from the line 2—2 of Figure 1.

Figure 3 is a central longitudinal section through my machine, as taken on the line 3—3 of Figure 2.

40. Figure 4 is a detail elevation of one of the clamping jaws.

Figure 5 is a detail cross section through a portion of one of the clamping jaws, as taken on the line 5—5 of Figure 4.

45. Figure 6 is a detail elevation of one of the jaw-holding members.

Figure 7 is a detail section as taken on the line 7—7 of Figure 6.

50. Figure 8 is a rear side elevation of the adjustable stop member.

Figure 9 is a longitudinal section through the adjustable stop member, as taken on the line 9—9 of Figure 8.

55. Figure 10 is a front elevation of my machine with an armature secured therein.

Figure 11 is a top plan view of my machine with an armature secured therein, as taken from the line 11—11 of Figure 10.

Figure 12 is a front elevation of the central portion of the body member.

Similar indices denote like parts throughout the several views.

In order that the construction, the operation, and the advantages of my invention may be more fully understood and appreciated, I will now take up a detailed description thereof, in which I will set forth the same as fully and as comprehensively as I may.

In the drawing, the numeral 1 denotes the body portion of my machine, said body portion having the base portions 2 and 3 formed integrally therewith and extending outwardly therefrom. The base portions 2 and 3 have the slots 2' and 3' formed therebetween for the purpose hereinafter set forth. Each of the outwardly extending portions 2 and 3 have smooth-bored apertures 2'' and 3'' respectively formed therethrough, said apertures 2'' and 3'' being parallel with relation to each other. The body portion 1 also has the forwardly extending lugs 4, 5, 6 and 7 formed integrally therewith, each of said lugs having an aperture formed therethrough for the reception of the threaded bolts 8 and 9, the bolt 8 extending through the apertures which are formed through the lugs 4 and 5, and the bolt 9 extending through the apertures which are formed through the lugs 6 and 7 and for the purpose hereinafter set forth. The lugs 4, 5, 6 and 7 also provide guides for the adjustable stop 10 which is slidably located therebetween. The stop 10 has the rearwardly extending side members 10' formed integrally therewith, said side members 10' being adapted to contact one of the inner surfaces of each of the forwardly extending lugs 4, 5, 6 and 7, said adjustable stop member 10 also has the rearwardly extending fingers 10'' formed integrally therewith, said fingers having the slots 10'' formed therebetween for the purpose hereinafter set forth. Extending rearwardly from the central portion of the member 10 are the threaded stems 45

10^b and 10^c, said stems being adapted to register with the smooth-bored apertures 1' and 1'' of the member 1. Threaded onto the stems 10^b and 10^c are the adjusting nuts 10^d and 10^e, said adjusting nuts being formed circular in shape and having their outer peripheries serrated as shown in Figure 8.

Extending forwardly from the members 2 and 3, and hingedly secured thereto are the jaw-holding members 11, each of said members 11 have the 55

portions **11'** formed integrally therewith and extending at right angles thereto, said portions **11'** having the smooth-bored apertures **11a** formed therethrough, each of said apertures **11a** being **5** adapted to register with the apertures **2''** and **3''**, and each of the members **11** being hingedly secured to their respective base portions **2** and **3** by the bolts **28** and **29** respectively. Extending through the central portion **11** is the circular **10** aperture **11b** and the slotted aperture **11c**, the purpose of which will be hereinafter set forth.

Extending outwardly from between the lugs **4** and **5** is the threaded hinge-bolt **12**, said hinge-bolt **12** being secured therebetween by means of **15** the bolt **8**, and likewise, extending outwardly from between the lugs **6** and **7** is the hinge-bolt **13**, said hinge-bolt **13** being hingedly secured therebetween by means of the bolt **9**. The hinge-bolts **12** and **13** have the head portions **12'** and **20** **13'** respectively formed integrally therewith, each of the head portions having an aperture formed therethrough, and through which the respective bolts **8** and **9** are secured.

Secured to the jaw-holding members **11** are the **25** jaw members **14**, each of said jaw members **14** having an aperture **14'** formed therethrough and each of said apertures **14'** being adapted to register with its respective hinge-bolt. Also formed through the member **14** is the threaded aperture **30** **14''**, through which the jaw members **14** are secured to their respective jaw-holding members **11** by means of their respective screws **15**. The jaw members **14** extend forwardly and then curve inwardly forming the curved portion **14a**, and terminate by forming the blade portion **14b**. The jaw members also have formed integrally therewith the shoulder portions **14d** which is adapted to be clamped against the outer surface of an armature. Projecting rearwardly and angularly from one **40** end of the curved portion **14a** is the arm portion **14c** and which is adapted to guide a wire into the slots of an armature during the process of winding the same.

On each of the threaded hinge-bolts **12** and **13** **45** are the respective coil springs **16** and **17**, one end of each being adapted to press against the head portion of its respective hinge-bolt, and the opposite end of each of said springs being adapted to exert pressure against the inner face of its respective jaw member **14**.

Threaded onto the outer end of each of the hinge-bolts **12** and **13** are the wing-nuts **18** and **19** respectively, and which are adapted to be turned against their respective jaw-holding members **11**.

Extending rearwardly from the body member **1** **55** is the shaft **20**, and which may be formed integrally therewith or attached thereto in any well known manner. The shaft is adapted to extend through a bearing block **21** which is supported by the bracket **22**, and which is adapted to be secured to a bench **27** or other suitable support by means of the bolts or lag screws **23**. The shaft **20** is adapted to have a crank **26** attached to its rear end as shown in Figure 1.

When it is desired to operate my machine by power, the shaft **20** may be detached therefrom and the base portion secured to the face plate of a lathe or other power machine by means of bolts inserted through the slots **2'** and **3'**.

The numeral **24** denotes an armature having the slots **24'** formed therethrough, and **25** denotes the wire which my machine is adapted to wind **70** onto the armature.

The operation of my machine is substantially as follows—

With the jaw members **14** extended as shown in Figure 1, the armature **24** is inserted therebetween, the stop **10** being adjusted, by the nuts **10d** and **10e** so that the armature **24** is in position for the blade portions **14b** to engage two of the slots **24'**. Only the blade portions **14b** extend into the slots **24'** and the shoulder portions **14d** are clamped against the outer periphery of the armature **24** by tightening the wing-nuts **18** and **19** against their respective members **11**, to which the jaw members **14** are secured. After the armature **24** is thus secured between the jaw members **14**, as shown in Figure 11, a wire **25** is drawn from a spool (not shown) to the armature, and the free end of the wire is then secured in one of the slots **10a** where it is held securely, and the machine is then ready for operation.

As the crank **26** is turned, causing the shaft **20** **20** to rotate, which being secured to the body portion **1**, and causing the entire machine, together with the armature, to rotate. As the armature is rotated, the wire **25** being held securely in one of the slots **10a**, is drawn around the armature, the **25** arms **14c** of the jaw members **14** guide the wire **25** toward the curved portions **14a** of the members **14**, after which the wire **25** is guided by the jaw members into the respective slots **24'** of the armature **24**. After the correct number of turns **30** of wire have been wound into the first pair of slots **24'** and the wire removed from its slot **10a**, one of the wing-nuts is loosened and thereby releasing one of the blade portions **14b** from its respective slot **24'**. The armature **24** is then **35** rotated until the succeeding slots **24'** are in register with the blade portions **14b**, the wing-nut is again tightened against its respective member **11**, and the shoulders **14d** are in clamped relation with the armature **24**, after which the **40** free end of the wire **25** is again secured in one of the slots **10a** and the operation of winding the wire is repeated.

The above described operation is repeated until all of the slots have been properly wound with **45** the wire, and the completely wound armature is removed.

When it is desired to wind an armature having helically extending slots, the screws **15** may be loosened and the jaw members **14** pivoted so **50** that the blade portions **14b** thereof will conform to the angularity of said armature slots, after which the screws **15** may be tightened, and thereby holding the jaw members in the required position.

I desire that it be understood that my machine may be operated by a power lathe or the like as efficiently as with a hand crank.

I also desire that it be understood that minor changes may be made in the several details, and in the arrangement of the parts herein shown and described, without departing from the spirit of my invention or sacrificing any of the advantages thereof which are new and useful, and which involve invention.

Having now fully shown and described my invention, what I claim and desire to secure by Letters Patent of the United States, is—

1. An armature winding machine comprising **70** a single unit having a base portion having outwardly extending lugs, said lugs being adapted to be secured to a source of power, a jaw-holding member hingedly secured to each of said outwardly extending lugs, a plurality of jaw members each of which is adapted to be removably secured **75**

to said hinged members, each of said jaw members having a rearwardly and outwardly projecting arm, blade portions carried by said jaw members and adapted to engage the edge of a slot in an armature, shoulder portions carried by the jaw members and adapted to be secured against the outer surface of an armature, said projecting arms being adapted to engage and to guide a wire into the slots of an armature, and means for holding said jaws in clamped relation with an armature.

2. A machine for winding wire on armatures comprising a single unit and having in combination, a base portion, a body member formed integral therewith, forwardly extending jaw-holding members hingedly secured to said base portion, jaw members pivotally secured to said jaw-holding members, bolts hingedly secured to the body member and adapted to extend outwardly through said jaw members and said jaw-holding members, means for securely holding said jaw members in contact with an armature, means for adjusting an armature forwardly and rearwardly with relation to said jaw members, means provided by said jaw members for guiding a wire into the slotted portions of an armature, and means formed integral with said jaw members for holding an armature in clamped position, all substantially as shown and described.

3. An armature winding machine, having in combination, a base portion, a body member formed integral with said base portion, a plurality of forwardly extending jaw-holding members hingedly secured at their rear ends to said base portion, jaw members pivotally secured to said forwardly extending members, outwardly extending bolts secured to the central portion of said body member, said bolts being adapted to extend outwardly through apertures formed in said forwardly extending members, means adapted to be threaded onto said hinged bolts and adapted to contact the outer surfaces of said forwardly extending jaw-holding members, compression springs adapted to normally hold said forwardly extending members in contact with said means, each of said jaw members having an outwardly and rearwardly extending arm formed integrally therewith, a blade portion carried by each of said jaw members, said blade portions being adapted to engage the edge of a slot formed in an armature, said outwardly and rearwardly extending arms being adapted to engage and guide a wire into the slots of an ar-

mature, shoulder portions carried by the jaw members and adapted to be secured against the outer surface of an armature, and means for rotating said winding machine, all substantially as shown and described.

4. A unitary armature winding machine comprising in combination, a base portion having outwardly extending lugs, a jaw-holding member hingedly secured to each of the lugs, a jaw member pivotally secured to each of said jaw-holding members, each of said jaw members having a shoulder portion formed integral therewith and adapted to be clamped against an armature and to securely hold the same in the correct position to be wound with wire, said jaw members having blade portions formed integral therewith and adjacent to said shoulder portions, said jaw members having outwardly and rearwardly projecting arms formed integral therewith and adapted to engage armature wire and guide the same into position to be finally guided into an armature slot over one side of said blade portion.

5. An armature winding machine comprising a single unit having in combination, a base portion adapted to be revolvably supported, a body portion formed integral with said base portion and extending forwardly therefrom, jaw-holding members hingedly secured to said body portion and extending forwardly therefrom, hinge-bolts secured to said body portion and extending outwardly therefrom, a jaw member pivotally secured to each of the jaw-holding members and adapted to be adjusted inwardly and outwardly with relation to the body portion by means of the hinge-bolts, a compression spring carried by each hinge-bolt, a winged-nut threaded on the outwardly extending end portion of each hinge-bolt, said jaw members being adapted to be adjustably secured on each of said hinge-bolts between one end of a compression spring and a winged-nut, an arm formed integral with each of said jaw members and extending outwardly and rearwardly therefrom, said rearwardly and outwardly extending arms being adapted to engage and guide wire into a slot of an armature, a blade portion carried by each of said jaw members and adapted to extend into an armature slot, and a shoulder portion formed integral with each of said jaw members, the same being adapted to be clamped against an armature, all substantially as shown and described.

JAMES L. McNEILL.
